(57) **CLAIM**

I claim the ornamental design for a multicolor drafting device, as shown and described.

DESCRIPTION

FIG. 1 is a perspective view of a multicolor drafting device showing my new design;

FIG. 2 is a top plan view thereof;

FIG. 3 is a front, rear, left & right elevational view thereof; all being a mirror image thereof; and,

FIG. 4 is a bottom plan view thereof.

1 Claim, 1 Drawing Sheet

FIG. 1

FIG. 2

FIG. 3

FIG. 4
